ATTORNEY.

UNITED STATES PATENT OFFICE.

HOMER W. STIMMEL, OF WILKINSBURG, PENNSYLVANIA.

DESIGN FOR A WINDOW-BLIND SUPPORT.

SPECIFICATION forming part of Design No. 32,531, dated April 17, 1900.

Application filed March 12, 1900. Serial No. 8,414. Term of patent 3½ years.

To all whom it may concern.

Be it known that I, HOMER W. STIMMEL, a citizen of the United States, residing at Franklin street, Wilkinsburg, in the county of Allegheny and State of Pennsylvania, have invented a certain new and original Design for Window-Blind Supports; and I do declare the following to be a full, clear, and exact description of the invention, such as will enable others skilled in the art to which it appertains to make and use the same, reference being had to the accompanying drawing, and to the letters of reference marked thereon, which forms a part of this specification.

This invention relates to a new and original design in a window-blind support.

As shown in the accompanying drawing, the leading or material features of my design consist of a body A, circular in cross-section, with a screw-thread B formed thereon, which

terminates in a point at one end. The opposite end is bent in a semicircular form at C, so that the portion of the body at A' will be at an inclination of about forty-five degrees. The body is again bent at D, so that the end A'' will be parallel with the portion A', thereby forming a U-shaped hook upon one end of the body at about the angle specified.

Having described my invention, what I claim as new, and desire to secure by Letters Patent, is—

The design for a window-blind support, as herein shown and described.

In testimony whereof I affix my signature in presence of two witnesses.

HOMER W. STIMMEL.
